FORM FOR MAKING RUBBER ARTICLES

Abraham N. Spánel, Rochester, N. Y.

Application December 19, 1935, Serial No. 55,214

13 Claims. (Cl. 18—41)

This invention relates to forms for manufacturing thin rubber articles, and particularly from latex, and to a method of making such forms.

In the production of sheet rubber articles from latex it has been necessary in the past to provide forms made of wood, porcelain or glass, or cast from aluminum or the like and where such articles were made with reinforced margins by applicant, it has been necessary to provide forms of complicated contour. The designing and making of such complicated forms have been expensive and where a large number of such forms have been required, as in the manufacture of rubber articles on a quantity production basis, it has been necessary to invest large amounts of capital in forms, the time of making of which had to be necessarily long.

It is the purpose of the present invention to provide a simple type of form which obviates the need of casting in the making of the same but which can be manufactured from commercial sheet metal stock with a minimum amount of skill and at small cost.

The main feature of the present invention relates to a form made of sheet metal stock of desired outline and having attached thereto metal edging to develop therein a rubber article of any desired shape and with a margin reinforced by a ridge of rubber.

30. A further feature of the invention relates to a form having sheet metal pieces and bosses attached thereto to define reentrant or cut-out portions as well as openings in a rubber article deposited on the form.

35. The various features and advantages of the invention will appear from the detailed description and claims when taken with the drawings in which Fig. 1 is a front elevation of a form made according to the present invention; Fig. 2 is an enlarged vertical section, partially broken away, of the form taken substantially on the line 2—2 of Fig. 1; Fig. 3 is an enlarged fragmentary sectional view of the form with pieces of rubber layers thereon, said section being taken on the line 3—3 of Fig. 1; Fig. 4 is a cross section of the form taken on the line 4—4 of Fig. 1 also showing layers of rubber on the form; Fig. 5 is an enlarged fragmentary section taken on the line 5—5 of Fig. 1 indicating the character of the side margin of the form at which reinforced edges are generated in the garments deposited on the form; Figs. 5A, 5B, 5C and 5D are modified side margins for the form which may be substituted for that shown in Fig. 5; Fig. 5E is an enlarged sectional view of the form margin illustrated in

Fig. 5 also indicating the character of garment reinforcements generated at said margin; Fig. 6 illustrates a blank which is the main part of the form of Fig. 1; Figs. 7, 8 and 9 illustrate stampings which may be attached to the faces of the blank of Fig. 6 in constructing the form shown in Fig. 1; Fig. 10 is a front view of a modified form for making bibs, aprons and the like; Fig. 11 is a modified form for making sheets, table covers and the like; and Fig. 12 is a modified type of form on which a latex rubber curtain or the like can be made.

Referring to Figs. 1 to 9 inclusive of the drawings, there is illustrated a form for making rubber aprons, bibs and the like. This form comprises a sheet metal plate 5 stamped or cut from sheet aluminum or stainless steel of any desired thickness, and having the outline best illustrated in Fig. 6. The portion of the form which generates the neck opening in the apron includes 15 a piece 6 stamped or cut from sheet metal (see Fig. 8). One such piece is attached to each of the faces of the plate at the top thereof. These stamped out pieces are preferably fastened to the plate as by soldering and/or welding so that there will be no crack between the plate and the attached pieces. The upper part of the bib-generating area of the form which is illustrated at the top of Fig. 1, terminates in abrupt edges in the surfaces of the plate 5. In order to define 20 the margins of the form from the waist portion thereof to the neck portion of the same as well as to define one margin of each of the form areas on which the tying strips or strings, are deposited, a pair of stamped or cut-out sheet metal 25 pieces 7, of the outline illustrated in Fig. 7, are attached to each surface of the plate 5 in the position shown in Fig. 1, by any suitable means such as by soldering and/or welding. The bottom portion of the form as illustrated in Fig. 1, 30 which portion develops the bottom of the deposited apron, has fastened to each surface thereof, a stamped or cut-out piece 9. Each piece 9 has slots therein to define hooks 10 and is attached to the portion 11 of the plate 5 which 35 has similar slots therein to define hooks 12, so that the hook portions 10 and 12 are in registry. The several pieces are attached to the main plate in this position as by soldering and/or 40 welding or the like. It will be understood that when this form is being used for making aprons, it is supported by the mentioned hook like 45 portions.

The edges of the main plate from the corners 50 thereof to each end of the pieces 9 are bounded 55

by an edge-defining strip 14 as shown in Figs. 3, 5 and 5E. This strip is preferably made from sheet stock having a groove 15 or the like rolled or formed therein so that the sides of the groove 5 can engage both surfaces of the plate but with the abrupt edges of the strip projecting away from the principal plane of the plate. This strip is attached to the plate by soldering or by welding, or by both, indicated at 16 (Fig. 5E) so that 10 the junction between these two parts is free from crevices.

Each surface of the plate 5 near the neck portion thereof is provided with pairs of bosses 17 to define buttonholes in the deposited apron and 15 is also provided near each side edge thereof with a boss 18 at a point near where the tying strip portion of the form meets the main surface of the form. Each of the mentioned bosses may terminate in an abrupt edge. By reason of the 20 bosses 18, holes with reinforced margins are developed in the deposited apron strings at these points. Thus the end of each apron tie or string can be reinserted through its related opening so that the apron ties or strings which are deposited 25 in such a direction that they tend to extend toward the neck of the apron, when inserted through the opening will project at right angles to the apron.

It will be understood that the reinforcing strip 30 14 can be made in various ways. As shown in Fig. 5A there is provided a bar of readily bendable stock rectangular in cross section which has a notch or kerf 20 cut in one face thereof, the width of the kerf being sufficient to receive the edge of 35 the plate 5 for soldering therein.

In the modified arrangement shown in Fig. 5B, the margin 5a of the plate 5 is bent as a flange at suitable angles to the main plane thereof and a narrow flat strip 21 of sheet material is soldered 40 to the bent over margin of the plate.

In the further modified arrangement shown in Fig. 5C the plate 5 is made of two thin plates 5b which have their edges turned over as indicated 45 at 5c to provide flanges. The junction of the two plates at these two flanges is welded or filled with solder 23 by which the two plates are firmly joined together.

In the modification shown in Fig. 5D the main 50 plate 5 is formed of two plates 5d to the edge of which there is fastened a strip 24 projecting beyond each surface of the plate in the nature of a flange.

A better understanding of the structure of the 55 form may be obtained by describing the method in which it is used to deposit two rubber aprons simultaneously. One or more of the forms in position inverted from that shown in Fig. 1 are supported by the hooks 10 on a suitable rack or 60 support (not shown). The forms in this position are then submerged one or more times into a bath of an aqueous dispersion of rubber or the like with a "setting" or drying interval between each dip, until a layer of rubber 26 of desired 65 thickness is deposited on each surface of the form. At the junction between the plate 5 and the pieces 6, 7 and 9 as well as at the junction of the plate with the strips 14, the rubber of the layer will accumulate as indicated at 27, while at 70 the sharp or abrupt edges of these pieces and strips the rubber layer will develop a line of weakness therein so that the rubber on these pieces and strips can be torn away at this line of weakness leaving the reinforced margin 27 of each 75 layer with a torn or feather edge 28. Similarly

at each of the bosses such as 17 and 18, the rubber will accumulate in the junction between the bosses and the plate 5 to provide a reinforced margin 29 for each of the resulting holes in the layer, this margin terminating in a torn or feather edge 30. Adjacent the lower edges of the plate 5, the rubber will accumulate as a reinforcement 31 which is semi-oval or semi-pear shaped in cross section, while at these edges of the plate a line of weakness 32 will develop in the deposited layer 10 so that the layer can be parted at this point. After the layer has properly "set" or dried on the form, the excess portion thereof on the faces of the pieces 6, 7 and 9 as well as on the edge strips 14 is torn away leaving two rubber aprons 15 or bibs which can be stripped from the form.

A modified type of form 35 for making aprons, bibs and the like is shown in Fig. 10. This form comprises a plate 36 cut or stamped from sheet metal to any desired outline, for example, that 20 shown. At each surface of this plate and at the top thereof, there is secured by soldering and/or welding, a cut-out or stamped out plate 37 similar to piece 6 illustrated in Fig. 8. A relatively thin strip of sheet metal 38, which is similar to 25 the strip 14 of Fig. 5E is shaped to conform to the outline of plate 36. The edge of this plate is inserted in the groove in the strip where it is soldered and/or welded in the manner best indicated in Fig. 5E so that there are no crevices or 30 cracks between the strip and the plate. It will be noted that the ends of the strip 38 engage the side edges of the pieces 37 being soldered and/or welded thereto. Each face of the plate 36 is preferably provided with bosses 39, each of which 35 terminates in an abrupt edge similar to that of the bosses 17 best shown in Fig. 4. It will be understood that pieces 37 and the strip 38 develop a reinforced margin for the apron deposited on each surface of the form while the bosses 39 40 develop openings therein with reinforced margins through which tie-strings or the like may be inserted.

The modified type of form 40 shown in Fig. 11, is adapted for making rubber sheets or rubber 45 table covers. This form comprises a plate 41 cut or stamped from sheet metal or like material to any desired outline such as indicated. A thin sheet metal strip 42, of the character best illustrated in Fig. 5E, is attached to the edge of the 50 plate 41, this edge being inserted in the groove in the strip 42 where it is fastened by soldering and/or welding so that there are no cracks or 55 crevices between the strip and the plate. The ends 43 of the strip are likewise soldered or welded together. If it is desired to provide openings in the corners of the resulting sheets deposited on this form, a boss 44 of the character indicated at 17 in Fig. 4, is soldered and/or welded at each corner and on each surface of the plate. 60

In Fig. 12 there is illustrated a form 50 suitable for making rubber curtains. This form comprises a rectangular plate 51 which is cut or stamped from suitable sheet metal. This plate which preferably has rounded corners is provided 65 at its top and sides with a reinforcement-developing strip 52 of the character illustrated in Fig. 5E. It will be understood that the edges of the mentioned top and sides of the plate are inserted in the groove in the strip 52 where they are 70 fastened by soldering and/or welding. It will be noted that the ends 53 of the strip 52 terminate just short of the rounded lower corners of the plate. These lower corners of the plate as well as the lower edge 54 thereof, may be abrupt or 75

may terminate in a knife edge. Where it is desired that the deposited curtains have a row of openings along one end thereof, each surface of the form near one end thereof is provided with a row of bosses 55 which terminates in an abrupt edge as indicated at 17 in Fig. 4.

It will be understood from the foregoing description that in using the forms in Figs. 10, 11 and 12 in making the rubber articles, these forms are dipped one or more times with a drying or setting interval between each dip until a layer of the desired thickness is deposited on the form. At the junction between the strips 38, 42 and 52 and the plates 36, 41, and 51, respectively, a reinforcing ridge of rubber will accumulate in the layer of the character indicated at 27 in Figs. 3 and 5E. At the junction between the pieces 37, the raised bosses 39, 44 and 55 and the plates 36, 41 and 51 respectively reinforcing ridges of the character indicated at 27 and 29 in Fig. 4 will be developed in the layer. It will be understood that the layer adjacent the outside of the reinforcement will be torn or cut to give the desired outline to the finished article. In the case of the article developed on the form of Fig. 12, the lower margin thereof adjacent the abrupt edge 54 will have a cross section semi-pear-shaped or semi-oval in outline as indicated at 31 in Fig. 4.

It will be appreciated that with the forms of the present invention articles of two different types, styles or sizes may be made simultaneously on opposite sides of the form, for example, with the construction illustrated in Fig. 5B an apron of a large size may be made on one face of the form and an apron of smaller size may be made on the other face thereof. Also an apron or bib as shown in Figs. 1 and 10 can be made on one face of the form and a sheet or curtain as shown in Figs. 11 and 12 can be made on the other face of the form.

What I claim is:

1. A dipping form for making a thin rubber article having a reinforced edge, said form comprising a plate of sheet material to which a layer of liquid rubber will adhere, said plate being cut to approximately the outline of the desired article, and a flange attached to a substantial portion of the margin of said plate, said flange projecting from a surface of said form a distance at least equal to the desired thickness of the reinforced edge of the article whereby a rubber article having a reinforced margin can be deposited on said form, and means for supporting said form with its principal plane in an upright position.

2. A dipping form for making a thin rubber article having a reinforced edge, said form comprising a plate of sheet material to which a layer of liquid rubber will adhere, said plate being cut to approximately the outline of the desired article, and a flange attached to a substantial portion of the margin of said plate, said flange projecting from a surface of said form a distance greater than the thickness of the rubber layer to be deposited on said surface whereby a rubber article having a reinforced margin can be deposited on said form, and means for supporting said form with its principal plane in an upright position.

3. A dipping form for making a thin rubber article having a reinforced edge, said form comprising a plate of sheet material cut to approximately the outline of the desired article, sheet-like pieces attached to the face of the plate to define re-entrant edges of the article, and a

flange of material attached to a substantial portion of the margin of said plate, said pieces and said flange projecting beyond the surface of said plate a distance at least equal to the desired thicknesses of the reenforced edges of the article. 5

4. A dipping form for making a thin deposited rubber article having a reinforced edge, said form comprising a plate of sheet material to which a layer of liquid rubber will adhere, said plate being cut to approximately the shape of the desired article, and a flange integral with a substantial portion of the margin of said plate, said flange projecting beyond the surface of said plate a distance at least equal to the desired thickness of the reinforced edge of the article. 10 15

5. A dipping form for making thin deposited rubber articles comprising two plates of sheet material cut to approximately the outline of the desired article and a flange formed on a margin of each of said plates, said plates being joined together with their edges in substantial registry. 20

6. A dipping form for making a thin rubber article having a reinforced edge, said form comprising a plate of sheet material to which a layer of liquid rubber will adhere, said plate being cut to approximately the outline of the desired article, and a strip conforming to and joined to a substantial portion of the edge of said plate, said strip projecting beyond the face of said plate a distance at least equal to the desired thickness 30 of the reinforced edge of the article.

7. A dipping form for making thin rubber articles having reinforced edges, said form comprising a plate of sheet material to which layers of liquid rubber will adhere, said plate being cut to approximately the outline of the desired article, and a strip conforming to and attached to a substantial portion of the edge of said plate, said strip projecting beyond each face of said plate a distance at least equal to the desired thickness 40 of the reinforced edges of the articles.

8. A dipping form for making thin rubber articles having a reinforced edge, said form comprising a plate of sheet material to which layers of liquid rubber will adhere, said plate being cut to approximately the outline of the desired article, and a strip of bendable material having a groove therein, a substantial portion of the edge of said plate being attached to said strip in said groove whereby said strip projects beyond each 50 face of the plate as a marginal flange to generate integral reinforcing ridges at the edges of the articles.

9. A dipping form for making a thin rubber article having a reinforced edge, said form comprising a generally rectangular plate with a curved end extension cut from sheet material to which liquid rubber will adhere, and a piece of sheet material having an enlarged portion and a reduced portion superimposed on and attached to 60 a surface of said extension and to the adjacent portion of said plate, said reduced portion extending approximately to the edge of said curved extension to define an opening in said article. 55

10. A dipping form for making a thin rubber article having a reinforced edge, said form comprising a generally rectangular plate with a curved extension on one end cut from sheet material to which liquid rubber will adhere, a piece of sheet material having an enlarged portion and a reduced portion superimposed on and attached to a surface of said extension and to the adjacent portion of said plate whereby an opening is 70 generated in the resulting article, said reduced portion extending approximately to the edge of 75

5 said curved extension to define an opening in said article, and a raised flange attached to substantial portions of the margin of the sides and other end of said plate and projecting to an abrupt edge adjacent the surface of said plate whereby a reinforcing ridge is generated in a portion of the margin of the resulting article.

11. A dipping form for making a thin rubber apron having a reinforced edge, said form comprising a generally rectangular plate with a curved extension on one end cut from sheet material to which liquid rubber will adhere, a piece of sheet material having an enlarged portion and a reduced portion superimposed on and attached to a surface of said extension and to the adjacent portion of said plate, said reduced portion extending approximately to the edge of said curved extension to define a neck opening in said apron, a raised flange attached 10 to substantial portions of the margin of the sides and other end of said plate and projecting to an abrupt edge adjacent the surface of said plate whereby a reinforcing ridge is generated on certain margins of said apron, and an 15 elongated wedge-shaped piece of sheet material attached to said surface of said plate adjacent each side edge thereof, one long edge of each piece extending in spaced relation along its related side edge to define a tie for said apron, each piece having a long curved edge merging 20 with a curved edge of said extension to define a portion of the top portion of said apron.

12. A dipping form for making thin rubber

articles having reinforced edges, said form comprising a plate of sheet material to which a layer of liquid rubber will adhere, said plate being cut to approximately the outline of the desired articles, and a flange on each face of the plate on a substantial portion of the margin thereof, each flange projecting from a face of said plate a distance at least equal to the desired thickness of the reinforced edge of the articles, whereby a rubber article having a reinforced 10 margin can be deposited on each face of said form, and means for supporting said form with its principal plane in an upright position.

13. A dipping form for making a thin rubber apron having a reinforced edge, said form comprising a generally rectangular plate with a curved extension on one end cut from sheet material to which liquid rubber will adhere, a piece of sheet material to define a neck opening in the resulting apron attached to a surface of 20 said extension, a raised flange attached to substantial portions of the margin of the sides of said plate and projecting beyond the surface of said plate whereby a reinforcing ridge is generated on certain margins of said apron, and 25 elongated pieces of sheet material attached to said surface of said plate, said pieces extending in spaced relation along the side edges of said plate to define ties for said apron, each piece having an edge merging with a curved edge of 30 said extension to define a portion of the top portion of said apron.

ABRAHAM N. SPANEL.
